(57) **CLAIM**

The ornamental design for a bottle holder as shown and described.

DESCRIPTION

FIG. 1 is a front perspective view of a bottle holder, showing my new design;

FIG. 2 is a front view thereof;

FIG. 3 is a right side view thereof;

FIG. 4 is a rear view thereof;

FIG. 5 is a left side view thereof;

FIG. 6 is a bottom view thereof; and,

FIG. 7 is a top view thereof.

The bottle holder is shown with symbolic breaks, represented by wavy, broken lines. The wave broken lines and the portions of the bottle holder that are depicted in broken lines form no part of the claimed design.
